UNITED STATES PATENT OFFICE.

HENRY H. CUTLER, OF MILWAUKEE, WISCONSIN.

GAS-ENGINE.

1,231,500.

Specification of Letters Patent. Patented June 26, 1917.

Application filed June 17, 1915. Serial No. 34,599.

To all whom it may concern:

Be it known that I, HENRY H. CUTLER, a citizen of the United States, residing at Milwaukee, in the county of Milwaukee and 5 State of Wisconsin, have invented new and useful Improvements in Gas-Engines, of which the following is a full, clear, concise, and exact description, reference being had to the accompanying drawing, forming a 10 part of this specification.

My invention relates to improvements in explosive engines and has for one of its objects to provide means for more efficiently scavenging the engine cylinders of exhaust 15 gases after the explosion has taken place.

For the purpose of disclosing my invention I have illustrated one embodiment thereof, in which—

Figure 1 is a longitudinal section of a four- 20 cylinder engine embodying my invention;

Fig. 2 is a horizontal sectional view taken on the line *a—a* of Fig. 1;

Fig. 3 is a transverse section taken on the 25 line *b—b* of Fig. 1;

Figs. 4, 5, 6 and 7 are diagrammatic views 30 illustrating the relative positions of the engine cylinder pistons and the scavenging pistons.

Fig. 8 is a detail side elevation of the 35 scavenging piston operating mechanism; and

Fig. 9 is a sectional view on the line *c—c* 40 of Fig. 1.

In the embodiment illustrated, the engine 45 is provided with four cylinders, 1, 2, 3, 4, which are of the usual construction and are mounted above the crank casing 5. This crank casing is of the usual construction and provides a casing and bearings for the 50 crank shaft 6 of the engine, which shaft is connected by means of piston rods 7 with the pistons 8 of the respective cylinders. These cylinders are all provided with radiating ribs 9, as is usual, and surrounding 55 each cylinder is a casing or jacket 10, opened at its upper end 11 and also opened at its lower end 12. This jacket extends below the inclosing casing 13, at the rear end of which is arranged the usual cooling fan, 60 the air being drawn in through the opening 11 and out through the rear of the casing 13 by the fan attached to the fly wheel of the engine. Mounted on the top of each cylinder is a combustion chamber 14 which, 65 in effect, is a horizontally disposed cylinder

having radiating ribs 15 arranged thereon, as is the case with the engine cylinders, and having operating therein a scavenging piston 16. The in-take valves 17 and the exhaust valves 18 of each cylinder of the engine are disposed in the front of the combustion chamber 14. These valves, as shown, are horizontally mounted and are of the usual construction, being closed under the influence of coiled springs 19 interposed 70 between collars 20 on the ends thereof and collars 21 secured in the head of the cylinder 14. These valves are operated from the cam shaft 20, having operating cams 21^a thereon, between which and the ends of the 75 stems 22 of the valves are movable bearing members 23.

The scavenging pistons 16 are connected by piston rods 24 with rocking crank shafts 25, 26 and 27; that is, the scavenging piston 75 of cylinder 1 is connected with the crank shaft 27; the scavenging piston of cylinder 4 is connected with the crank shaft 26, the cranks on these respective shafts being disposed at an angle of 150 degrees. The 80 scavenging pistons of cylinders 2 and 3 are connected with the crank shaft 25, two cranks being formed on this shaft and being disposed at an angle of 150 degrees. The 85 crank shafts 27 and 26 are inter-connected 90 by an auxiliary shaft 28, having at either end thereof pinions 29 meshing with pinions 30 on the ends of the shafts 26 and 27, so that in effect the shafts 26 and 27 are one shaft. The scavenging pistons of the cylinders are thus connected in pairs, so that a movement imparted to one of the pistons of the pair by the operation of the piston of its engine cylinder will be imparted to the other piston of the same pair. The purpose of this will be more obvious in describing the operation. These crank shafts of the scavenging pistons are preferably set at 150 degrees, so that when the scavenging 95 piston is at its outermost limit of movement 100 the crank of its crank shaft will be in a direct line with the piston rod and a straight thrust may thereby be obtained, avoiding any tendency to twist the crank when the charge in the explosion chamber is ignited, 105 it being understood that the explosion takes place when the scavenging piston is at the outermost limit of its stroke. The scavenging pistons being arranged in pairs and the cranks thereof being set at an angle, the 110

crank shaft rocks back and forth under the movement of the pistons and one piston of the pair will move in as the other one moves out. In order to more fully understand the operation reference may be had to the diagrammatic views of Figs. 4 to 7 inclusive.

We will assume that the piston in cylinder 2 has completed its downward movement on its in-take stroke. On its upward movement it will be moving on its compression stroke, thereby tending to compress the charge therein. This compression stroke will be about half way completed when the compressed charge will commence to force the scavenging piston 16 of this cylinder outward. The outward movement of the scavenging piston 16 will cause an inward movement of the scavenging piston 16 in cylinder 3, the piston of this cylinder moving upward on its exhaust stroke, so that as the upward movement of the piston of cylinder 3 forces the exploded gases up, the scavenging piston 16 will force them horizontally 25 and out of the exhaust port, and by the time the piston of cylinder 3 has reached the uttermost limits of its upward movement the piston 16 will have likewise reached the uttermost limit of its inward movement, so that the exhaust gases will be forced out and the explosion chamber and cylinder thoroughly cleaned, ready for a fresh charge to be drawn in. The piston of cylinder 2 moving up on its compression charge, the piston 30 of cylinder 1 will be moving down on its explosive stroke and the piston of cylinder 4 will be moving down on its intake stroke. It is thus seen that on each compression movement of the piston of one of the engine cylinders the scavenging piston of that cylinder will be moved outward and thereby move the scavenging piston of the other of the pair of cylinders inward during the upward movement of its piston on the exhaust stroke. Of course, after the scavenging piston has been moved outward by the compression stroke of the piston of its cylinder it will have no further movement until after the explosion has taken place, and, in fact, until its twin 45 piston will be moved outward by the compression of the charge in its twin cylinder. The suction stroke, of course, will not cause the scavenging pistons to move inward, so that these pistons remain stationary except when they are forced inward by the compression of a charge in the opposite cylinder of the pair. By this arrangement the scavenging of the engine is accomplished without the unnecessary absorption of any of the power of the engine and without there ever being any danger of the scavenging piston moving against the explosion of the engine or "bucking" the engine. The scavenging pistons are not connected to any driven 60 member of the engine and receive their

movement only by the compression of the charge in the explosive chamber of the engine.

The cam shaft 20^a of the engine is driven from the main shaft 6 thereof. For accomplishing this, upon the end of the engine frame 5 I mount an inclosing casing 31, in which is arranged a driving pinion 32 directly mounted on the main shaft 6. A second casing 33 is mounted at the top of the air-cooling jacket of the first cylinder and mounted on the cam shaft which projects into this casing is a pinion 34. Passing over these respective pinions is a silent drive belt 35, which also passes over an idler pinion 36 mounted in the casing 31 and thereby drives the shaft 20^a from the main driving shaft. For the purpose of tightening the belt 35 I provide a roller 36^a which bears against the same and which is mounted on an adjustable stem 37 adjustable from the exterior of the casing 31. Surrounding the belt between the casing are a pair of tubular members 38 for protecting the belt.

While I have shown and described one embodiment of my invention, it will be understood that various changes may be made therein and the invention embodied in other constructions without departing from the spirit thereof as set forth in the appended claims.

Having thus described my invention, what I claim as new and desire to secure by Letters Patent, is:—

1. In an explosive engine, the combination with a pair of engine cylinders and pistons operating therein, of auxiliary scavenging means for said cylinders operated by the compression of a charge in each cylinder for forcing out the products of combustion from the other.
2. In an explosive engine, the combination with a pair of engine cylinders, of pistons operating therein, each cylinder being provided with an explosion chamber, and auxiliary means operated by the compression of the charge in each of said chambers for contracting the area of the opposite chamber after a charge has been exploded therein and for forcing out of said chamber the products of combustion.
3. In an explosive engine, the combination with a pair of engine cylinders and pistons therefor, of a pair of supplemental cylinders forming explosion chambers for said cylinders, pistons operating in said explosion chambers, and means operated by the compression of a charge in each of the engine cylinders for forcing inwardly the piston of the explosion chamber of the opposite engine cylinder for clearing said chamber of the products of combustion after an explosion has taken place.
4. In an explosive engine, the combination with a pair of engine cylinders and

- 5 pistons operating therein, of a cylinder angularly disposed with respect to the engine cylinder at the top of each of said engine cylinders and forming an explosion chamber, and means in each of said chambers operated by the compression of a charge in 50 the opposite engine cylinder for forcing out the products of combustion after an explosion has taken place.
- 10 5. In an explosive engine, the combination with a pair of engine cylinders, of a cylinder angularly disposed with respect to the engine cylinders at the top of each engine cylinder and forming an explosion chamber, horizontally disposed intake and 55 outlet valves in the head of each of said explosion chambers, and means operated by the compression of a charge in each engine cylinder for forcing out of the opposite explosion chamber the products of combustion.
- 15 6. In an explosive engine, the combination with a pair of engine cylinders and pistons operating therein, of a pair of cylinders mounted above said engine cylinders angularly disposed with respect thereto and 60 forming explosion chambers, scavenging pistons operating in said explosion chambers, and operated by the movement of one scavenging piston in one direction for moving the other in the opposite direction.
- 20 7. In an explosive engine, the combination with a pair of engine cylinders, of pistons operating therein, each of said cylinders having an explosion chamber, scavenging pistons operating in said explosion chambers for clearing the same of the products of combustion after an explosion has 65 taken place, said scavenging pistons remaining stationary on the explosion stroke of the corresponding engine-piston and being moved by the compression of a charge in the cylinder, and means operated by one scavenging piston for moving the opposite one.
- 25 8. In an explosive engine, the combination with a pair of engine cylinders, of pistons operating therein, each of said cylinders having an explosion chamber, scavenging pistons operating in said explosion chambers, and means operated by the compression of a charge in each engine cylinder for moving the scavenging piston of the opposite engine cylinder in a scavenging direction only on the movement of its corresponding engine piston on its exhaust stroke.
- 30 9. In an explosive engine, the combination with a pair of engine cylinders, of pistons operating therein, each cylinder being provided with a cylinder disposed angularly with respect thereto forming an explosion chamber at the top thereof, pistons operating in said cylinders for scavenging the gases of an exploded charge, cranks connecting said scavenging pistons together and disposed at such an angle that when the 70 scavenging piston is at the outermost limit of its stroke the crank and piston rod form a straight line and operating means for said explosion chamber pistons permitting them to remain stationary at the outermost limit of their strokes during the explosion movement of their corresponding engine pistons.
- 35 10. In an explosive engine, the combination with a pair of engine cylinders and pistons therefor, of an explosion chamber for each of said cylinders, auxiliary means for 75 scavenging the exploded charge in said explosion cylinders, operated by the compression of a charge in the opposite engine cylinder, and in-take and exhaust valves arranged in said explosion chambers angularly moving with respect to the engine cylinders.
- 40 11. In an explosive engine, the combination with a pair of engine cylinders and pistons therefor, of an explosion chamber 80 angularly disposed with respect thereto for each of said cylinders, auxiliary means for scavenging the said chambers of the explosion charge operated by the movement of the piston of the opposite engine cylinder 85 on its compression stroke, and in-take and exhaust valves in one end of each of said explosion chambers.
- 45 12. In an explosive engine, the combination with a pair of engine cylinders and pistons therefor, of an explosion cylinder angularly disposed with respect thereto for each of said engine cylinders, pistons operating in said explosion cylinders for scavenging the explosion cylinders of the products of 90 combustion, operated by the compression of a charge in the opposite engine cylinder, and in-take and exhaust valves in the heads of each of said explosion cylinders.
- 50 13. In an explosive engine, the combination with a pair of engine cylinders and pistons operating therein, of an explosion cylinder for each of said engine cylinders, pistons operating in said explosion cylinders, crank shafts for operating said explosive 95 cylinder pistons operatively independent of the engine crank shaft, the cranks of said shafts being so disposed that when the pistons of the explosive cylinders are at the outermost limits of their stroke the crank 100 shafts will be in a line parallel with the piston rods of said explosive cylinder pistons.
- 55 14. In an explosive engine, the combination with a pair of engine cylinders and pistons therefor, of an explosion cylinder angularly disposed with respect thereto for each of said engine cylinders, pistons operating in said explosion cylinders, and a crank shaft connecting said explosion cylinder 110 pistons operatively independent of the engine crank shaft, said crank shaft having its cranks so disposed that when the piston is at the outermost limits of its stroke the piston rod thereof and the crank of the 115
- 60 120
- 65 125
- 70 130

crank shaft will be in a straight line, the piston of one explosive cylinder being moved inward by the compression of a charge in the opposite engine cylinder.

- 5 15. In an explosive engine, the combination with a plurality of cylinders and pistons operating therein, each of said cylinders having an explosion chamber, of auxiliary scavenging pistons operating in said 10 explosion chambers, and a crank shaft operatively independent of the crank shaft of the engine for operating said scavenging pistons.
- 15 16. In an explosive engine, the combination with a plurality of cylinders, of pistons having an unvariable stroke operating therein, and means operated by the compression of a charge in one cylinder for forcing

out of the other cylinder the products of combustion.

17. In an explosive engine, the combination with a pair of engine cylinders, of pistons operating therein and a pair of auxiliary pistons, the compression of a charge in one engine cylinder operating one of said 25 auxiliary pistons and causing the same to operate the other piston to scavenge the opposite cylinder.

In witness whereof, I have hereunto subscribed my name in the presence of two witnesses.

HENRY H. CUTLER.
